Section 1, Public Law 690, August 8, 1946
Patent expires September 5, 1964

5 Claims. (Cl. 250—36)

1

This present invention relates to an electric circuit comprising a sawtooth oscillation generator of the blocking oscillator type and an amplifier or buffer stage for synchronising impulses to be applied to the said sawtooth oscillation generator and aims at reducing the time of the return stroke of the generated sawtooth waveform.

The blocking oscillator circuit may conveniently comprise a triode valve, but other types of valve may be used in known manner. The amplifier or buffer stage for the synchronisation impulses comprises a multi-electrode valve with at least three grids in which the first grid adjacent the cathode is adapted to function as a control electrode, the second grid as a screen or accelerating electrode and a third grid which will be referred to as an additional control electrode.

The present invention is concerned only with said multi-electrode valves of a type possessing the characteristic that when suitable operating potentials are applied to its electrodes, a voltage change applied to the additional control grid results in a current change in the opposite sense at the second grid, for example a change in voltage in the positive direction results in a decrease in current. The said second grid may be connected to other grids apart from those mentioned above while the valve retains the said characteristic. For example in a hexode valve containing four grids the fourth grid may be joined to the second grid so that both grids act as screen or accelerating electrodes, while the first and third grids act as before as control electrode and additional control electrode respectively. A substantially resistive load joined in the circuit of the second grid and any grids which may be associated with it, results in the said current change producing a voltage change across the said resistive load in the same sense as the voltage change at the additional control grid.

According to the invention a sawtooth oscillation generator of the blocking oscillator type including a valve having at least a control grid and anode is combined with a synchronising impulse amplifier or buffer stage incorporating a multielectrode valve of the type specified above in which in the said multielectrode valve, the control grid is adapted to receive synchronisation impulses, the anode is connected through a resistance or directly to a positive potential source, the second grid and any associated grids being connected by way of a substantially resistive impedance to a positive potential source while the additional control electrode is coupled to the control grid of the first-mentioned valve, characterised in that the said

2

second and associated grids are coupled by way of a small condenser to the control grid of the first-mentioned valve.

A modification of the present invention consists in the control grid of the synchronising impulse amplifier or buffer valve being adapted by means of a negative bias to suppress the electron emission from the cathode of the said valve except when a synchronising impulse is received.

10 The invention is particularly applicable to thermionic valves in which two electrode systems are incorporated in a single envelope such as a triode pentode or a triode hexode and a simplification of the circuit results when the third grid of the pentode or hexode section in this type of valve is joined internally to the control grid of the triode-section.

The invention will now be described with reference to the accompanying drawing. In the figure

20 a triode-hexode 1 is shown, the third grid 2 of the hexode section being internally connected to the control grid 3 of the triode section. The triode section is arranged in a blocking oscillator circuit, the usual over-coupled transformer being

25 denoted by 5, while 6 and 7 represent respectively the customary resistance and condenser in the grid circuit of the triode section. If the anode 4 of the triode section is joined by way of the transformer winding shown, to a suitable positive potential source e. g. by short circuiting resistance 8 the circuit operates with short bursts of radio frequency oscillations, at an oscillation frequency determined by the constants of the transformer and the stray capacities of the circuit. The short

30 bursts of oscillation result from the periodic charging and discharging of condenser 7 following the flow of current in the grid circuit of the triode section after oscillations have started; the oscillations cease when condenser 7 is charged to a certain value and recommence when this condenser has discharged by way of resistance 6. The said short bursts of oscillation result in corresponding short pulses of current in the anode circuit and by connecting resistance 8 and condenser 9 as shown a sawtooth voltage is produced

35 across the plates of condenser 9.

40 In order that synchronising impulses may be applied to the sawtooth oscillator the hexode section of the triode hexode 1 has its control (first) grid 10 adapted to receive the said impulses by way of coupling condenser 11 and resistance 12. The anode 13 of the hexode section is connected by way of a resistance 14 to a suitable positive source of potential. The second and fourth grids

45 15, 16 are joined and connected by way of re-

sistance 17 to a positive potential source, while grids 15, 16 are also joined by a small condenser 18 to the grid 3 of the triode section. The hexode section thereby behaves as a buffer stage with regard to synchronising impulses and if correctly set up amplification of these impulses may be obtained, which are then applied by way of condenser 18 to the blocking oscillator to enable synchronisation of the latter to be obtained in the known manner.

In addition to acting as a buffer stage with regard to synchronising impulses the hexode section also takes part in the generation of sawtooth oscillations by the triode section. The operation can be explained as follows: the impulse voltage normally occurring at the control grid 3 of the triode section during the short bursts of radio-frequency oscillation referred to above which occur during the return stroke or flyback of the sawtooth wave form, is transferred to third grid 2 by virtue of the direct connection between grids 2 and 3 and generates a voltage impulse in the same sense on the second and fourth grids 15, 16 of the hexode section. This voltage impulse at the second and fourth grids is transferred by the coupling condenser 18 back to grid 3 and results in an intensification of the voltage impulse at that grid, and therefore a corresponding increase in the anode current of the triode section. The time duration of the return stroke of the sawtooth oscillation is accordingly reduced, since the said anode current is obtained mainly from the charge on condenser 9, which is thereby discharged at an increased rate. This effect is the main advantage of the present invention since the time of the return stroke or flyback of the sawtooth wave form, which depends on the time taken to discharge condenser 9, is thereby reduced.

Currents flowing in the hexode section may influence the curvature of the "long" stroke of the sawtooth wave form produced by the blocking oscillator in which case a suitable negative bias may be applied to the control grid of the hexode in known manner whereby electronic emission from the cathode of the hexode section is substantially suppressed during the said long stroke, but is allowed when synchronising impulses of sufficient amplitude are received.

Typical values of the components of the circuit shown in the drawing for the generation of a 50 cycles/sec. time base voltage for television use, are as follows:

Condenser 11, 0.1 μ f.

Resistance 12, 1 megohm.

Resistance 17, 1 megohm.

Resistance 14, zero (direct connection)

Condenser 18, 200 micromicrofarads

Condenser 17, 10,000 micromicrofarads

Resistance 16, 1 megohm variable to zero. (Frequency control.)

Resistance 8, 1 megohm potentiometer with ends connected between H. T. supply and earth and the sliding contact connected to condenser 9 and the triode anode coil. (Amplitude control.)

Condenser 9, 0.003 μ f.

with an operating voltage of 250 v. as the high tension and -16 v. applied between the lower end of 12 and earth. The transformer 5 may consist of two coils of litz wire, closely coupled and having a dust iron core through the coils.

If a pentode valve is employed in place of the hexode valve as described above, the circuit arrangement differs only in that the screen grid between the additional control electrode and the

anode is omitted. In general this resultant modification will prove beneficial to the operation of the circuit.

I claim:

5. An oscillation generator comprising a blocking oscillator including a first discharge tube system having at least control grid and anode electrodes, and a synchronizing impulse amplifier for said oscillator, said amplifier including a second discharge tube system having at least control grid, accelerating grid, additional control grid and anode electrodes, the operating characteristic of said second tube system being such that with suitable operating potentials applied to said electrodes a change in potential at said control grid results in a current change in the same sense at said accelerating grid and a change in potential at said additional control grid results in a current change in the opposite sense at said accelerating grid, means to connect a positive potential to the anode of said second tube system, a load impedance, means to connect a positive potential through said impedance to the accelerating grid of said second tube system, a capacitor coupling the accelerating grid of said second tube system to the control grid of said first tube system, means connecting the additional control grid of said second tube system to the control grid of said first tube system, and means for applying synchronizing impulses to the control grid of said second tube system.

2. An oscillation generator comprising a blocking oscillator including a first discharge tube system having at least control grid and anode electrodes, and a synchronizing impulse amplifier for said oscillator, said amplifier including a second discharge tube system having in succession control grid, accelerating grid, additional control grid and anode electrodes, the operating characteristic of said second tube system being such that with suitable operating potentials applied to said electrodes a change in potential at said control grid results in a current change in the same sense at said accelerating grid and a change in potential at said additional control grid results in a current change in the opposite sense at said accelerating grid, means to connect a positive potential to the anode of said second tube system, a load impedance, means to connect a positive potential through said impedance to the accelerating grid of said second tube system, a capacitor coupling the accelerating grid of said second tube system to the control grid of said first tube system, means connecting the additional control grid of said second tube system to the control grid of said first tube system, and means for applying synchronizing impulses to the control grid of said second tube system.

3. An oscillation generator comprising a blocking oscillator including a first discharge tube system having at least control grid and anode electrodes, and a synchronizing impulse amplifier for said oscillator, said amplifier including a second discharge tube system having in successive arrangement a cathode, first, second, third and fourth grids and an anode, said first grid acting as a control electrode, said second and fourth grids being connected together and acting as an accelerating electrode and said third grid acting as an additional control electrode, the operating characteristic of said second tube system being such that with suitable potentials applied to said electrodes a change in potential at said additional control electrode results in a current change in the opposite sense at said accelerating electrode,

means to connect a positive potential to the anode of said second tube system, a load impedance, means to connect a positive potential through said impedance to the accelerating electrode of said second tube system, a capacitor coupling the accelerating electrode of said second tube system to the control grid of said first tube system, means connecting the additional control electrode of said second tube system to the control grid of said first tube system, and means for applying synchronizing impulses to the control grid of said second tube system.

4. An oscillation generator comprising a blocking oscillator including a first discharge tube system having at least control grid and anode electrodes, and a synchronizing impulse amplifier for said oscillator, said amplifier including a second discharge tube system having in successive arrangement a cathode, first, second, third and fourth grids and an anode, said first grid acting as a control electrode, said second and fourth grids being connected together and acting as an accelerating electrode and said third grid acting as an additional control electrode, the operating characteristic of said second tube system being such that with suitable potentials applied to said electrodes a change in potential at said additional control electrode results in a current change in the opposite sense at said accelerating electrode, means to connect a positive potential to the anode of said second tube system, a load impedance, means to connect a positive potential through said impedance to the accelerating electrode of said second tube system, a capacitor coupling the accelerating electrode of said second tube system to the control grid of said first tube system, means connecting the additional control electrode of said second tube system to the control grid of said first tube system, means to apply a negative cut-off bias to the control electrode of said second tube system, and means to apply synchronizing impulses to the control grid of said second tube system to overcome said cut-off bias and render said second tube system conductive for the duration of the impulse.

5. An oscillation generator comprising a blocking oscillator including a first discharge tube system having cathode, grid and anode electrodes, an over-coupled transformer having primary and secondary windings, one end of said primary being connected to grid of said first tube system, one end of said secondary being connected to anode of said first tube system, a resistance-capacitance parallel network connected between

the other end of said primary and cathode of said first tube system, a charging condenser connected between the other end of said secondary and cathode of said first tube system, a resistor, and means to connect a positive potential to said other end of said secondary through said resistor, and a synchronizing impulse amplifier for said oscillator, said amplifier including a second discharge tube system having in successive arrangement a cathode, first, second, third and fourth grids and an anode, said first grid acting as a control electrode, said second and fourth grids being connected together and acting as an accelerating electrode and said third grid acting as an additional control electrode, the operating characteristic of said second tube system being such that with suitable potentials applied to said electrodes a change in potential at said additional control electrode results in a current change in the opposite sense at said accelerating electrode, means to connect a positive potential to the anode of said second tube system, a load impedance, means to connect a positive potential through said impedance to the accelerating electrode of said second tube system, a capacitor coupling the accelerating electrode of said second tube system to the control grid of said first tube system, means connecting the additional control electrode of said second tube system to the control grid of said first tube system, means to apply a negative cut-off bias to the control electrode of said second tube system, and means to apply synchronizing impulses to the control grid of said second tube system to overcome said cut-off bias and render said second tube system conductive for the duration of the impulse.
